GEORGE E. MOLYNEUX, OF BAYONNE, NEW JERSEY, ASSIGNOR TO THE SINGER
MANUFACTURING COMPANY, A CORPORATION OF NEW JERSEY.

SEWING-MACHINE.

1,013,204.

Specification of Letters Patent.

Patented Jan. 2, 1912.

Application filed February 25, 1910. Serial No. 545,825.

To all whom it may concern:

Be it known that I, GEORGE E. MOLYNEUX, a citizen of the United States, residing at Bayonne, in the county of Hudson 5 and State of New Jersey, have invented certain new and useful Improvements in Sewing-Machines, of which the following is a specification, reference being had therein to the accompanying drawings.

10 This invention relates more particularly to that class of sewing machines provided with a tubular work-supporting arm or horn longitudinally of which the work is fed in stitching tubular articles; and it has 15 for its principal object to provide an end-cap for the work-support normally serving as a housing for the loop-taker, but capable of being shifted out of operative position to expose the latter for threading or adjustment 20 or for other purposes without being entirely detachable from the machine. As 25 preferably constructed, the end-cap has at the upper side of its closed end a longitudinal aperture or guideway having a comparatively narrow slit at the top and capable of 30 receiving the opened-out marginal portions of the lap seam to be presented to the covering stitch-forming mechanism comprising two needles and a single coöperating looper arranged crosswise of the direction of feed. 35 The work-supporting arm has a lateral undercut guideway extending longitudinally thereof to receive a slide-block or bar to which is pivotally connected an arm rigidly 40 attached to the cap; and a stop-pin is provided upon the throat-plate to prevent the swinging of the cap upon its slide-block or carrier until it has been withdrawn longitudinally sufficiently to clear the loop-taker 45 and prevent injury of the latter, whereby access is given to the loop-taker for threading or for adjustment or other purposes.

The invention will be understood by reference to the accompanying drawings, in 50 which—

Figure 1 is a front end view of the tubular work-support, the needles and presser-foot of a sewing machine such as that shown and described in my pending application 55 Serial No. 521,801, filed October 9, 1909, and Fig. 2, a side elevation, partly in section, representing the forward end of the work-support. Fig. 3 is a rear end view of the cap showing in section the throat-plate with 60 its side-shift stop, and Fig. 4 a plan of the

forward portion of the work-support, partly in section. Fig. 5 is a front end view of the work-support with the end-cap represented in section in inoperative position to expose the loop-taker.

As herein represented, the machine is provided with a reciprocating needle-bar 1 carrying the twin needle-clamp 2 in which are secured by means of the fastening screws 3 the shanks of two eye-pointed needles 4. 60 The presser-bar 5 has secured to its reduced lower portion by means of a fastening screw 6 the shank 7 of the presser-foot having pivotally connected therewith by means of the pin 8 the tilting foot portion 9 provided 65 in its forward portion with the guide-fin or keel 10 adapted to enter the angle between the united marginal portions of a lap seam flattened out to receive the covering stitches for the exposed raw edges. The tubular 70 horizontally extending horn or work-support 11 is provided with the usual arched throat-plate 12 secured thereon by means of screws 13 and having a flattened operative portion 14 extending beyond the extremity 75 of the arm and upon which the presser-foot normally rests. The top 14 of the throat-plate is provided with the longitudinal apertures or slots 15 for the laterally spaced 80 operative portions of the feed-dog 16 and needle apertures 17 connected by parallel slits 17* with the central feed aperture 15 to form a fabric-supporting tongue 18 intermediate and rearward of the needles.

The tubular end-cap 19 is shown of general cylindrical form with closed forward end and is cut away to form a recess in its upper side to receive the reduced forward portion of the throat-plate 12, one side of the recess affording a guide-shoulder 20 90 adapted to engage the head of a stop-screw 21 tapped in and depending from the bottom of the throat-plate at one side of one of its lateral feed-dog apertures 15. The circular forward end of the cap 19 whose peripheral portion extends in advance and somewhat above the flattened top of the throat-plate has formed therein a forwardly flaring and somewhat flattened upwardly inclined clearance aperture 22 leading into a 105 similarly inclined clearance groove 23 in the forward end of the throat-plate, and having leading into its top a longitudinally arranged central guide-slot 24, directed toward the space intermediate the needles, to admit 110

the previously stitched overlapped plies of fabric at the seam, the marginal portions of such plies entering the clearance aperture 22.

5 The end-cap 19 terminates at the rear extremity in an abrupt annular shoulder fitted to the forward extremity of the cylinder-arm 11, and adjacent such extremity its side wall is slightly thickened to form an 10 annular shoulder 25 adapted for engagement with the spring catch-plate 26 formed with an operative shoulder 27 and having its shank 28 let into a lateral recess in the arm 11 and secured therein by means of 15 the screw 29 and interposed block 30. By means of the catch-plate 26, which is arranged and operates wholly inside of the cap 19, the cap is held securely in operative position, but may be readily disengaged 20 therefrom by a slight effort of the operator, as the shoulder 27 of the catch-plate is somewhat inclined to the direction traversed in the shifting of the cap. As shown herein, the cap has secured in its inner wall the reduced forward end of a backwardly extending 25 rigid arm 31 which is notched at its rearward end and pivotally connected by means of a transverse pivotal pin 32 with a tongue 33 formed upon the forward end 30 of a slide-bar or block 34 of slightly dove-tailed cross-section which is fitted to a correspondingly formed lateral slideway 35 formed within and extending longitudinally of the arm 11. The arm is provided 35 adjacent the slideway 35 with an inner slot or recess 36 whose forward end affords a positive stop-shoulder 36^x for the reduced inner end portion 37 of a screw-pin 38 tapped into the slide-bar 34 and adapted by 40 its engagement with the forward stop-shoulder of the slot 36 to limit the outer motion of the cap when withdrawn from operative position. By forming both of the members 31 and 34 of similar undercut cross-section, 45 not only are they both adapted for free movement and guidance within the similarly formed slideway 35 of the arm 11, but the slideway acts upon the arm 31 to guide the same in controlling the shifting movement 50 of the cap axially of the work-supporting arm, while both are confined in operative relation with the arm 11.

As described more fully in my said application, the shank of the single eye-pointed 55 looper 39 which co-operates with the needles 4, in the production of the covering seam, is secured in the tilting carrier 40 mounted upon a fulcrum-pin 41 sustained by an arm 42 of the looper-supporting and actuating 60 rock-shaft, the carrier having guide-wings 43 affording a slideway for a block 44 which is carried by a jogging member 45 for rocking the looper upon its fulcrum-pin 41 to produce the sidewise needle-avoiding movements of the same. As the looper is dis-

posed in practice in advance of the front wall of the cylinder-arm 11, it is desirable that in shifting the cap 19 into inoperative position it be at first drawn forward to enable its rear end to clear the looper mechanism, and then swung laterally into the retracted position represented in Fig. 5 for access to the looper mechanism. To this end, the stop-pin 21 is fixed upon the forward portion of the throat-plate, whereby 70 its engagement with the guide-shoulder 20 of the cap insures that the latter be drawn outwardly in the axial line of the arm 11 until its rearward extremity clears such pin, when it is free to be turned aside. In returning the cap to operative position, the pin 21 acts similarly to prevent the premature longitudinal movement of the cap toward the end of the arm 11 while in eccentric relation therewith so as to render 80 the looper mechanism liable to injury or disarrangement thereby.

In feed-up-the-arm machines as heretofore constructed, it has been proposed to apply to the outer end of the arm for housing the loop-taker a cap which is wholly removable. This has been objectionable, because it necessitated the operator laying the cap down upon the sewing machine supporting table after detachment, with the liability of its being dropped upon the floor under the jarring action of the adjacent machinery, and because it required the employment of guide-bars or rods working in sockets from which they were wholly removed and which were liable to become clogged by introduction of lint and dirt so that after continued use the cap could not be returned wholly to working position. By the present improvement, the end-cap cannot by any possibility be dropped or mislaid, and the slideway for its movable support is never wholly vacated, and is furthermore arranged at the side of the arm where there is little liability of accumulating 100 lint and dirt.

While the present improvement, as herein represented is specially adapted for performing the covering operation above described, it is to be understood as not limited 115 in all its features to embodiment in machines for this class of work, and it is also evident that the improvement is susceptible of considerable modification in construction and arrangement of its several parts without departure from the scope of the invention.

Having thus set forth the nature of the invention, what I claim herein is:—

1. In a sewing machine, the combination 125 with a tubular work-supporting arm, of a longitudinally movable slide mounted thereon, an end-cap fitted to the outer extremity of the arm and affording a housing for a loop-taker mounted in said arm, and a piv- 130

total connection between said cap and the slide.

2. In a sewing machine, the combination with a tubular work-supporting arm, of a longitudinally movable slide mounted thereon, an end-cap fitted to the outer extremity of the arm and affording a housing for a loop-taker mounted in said arm, a pivotal connection between said cap and the slide, and a stop for determining the range of longitudinal movement of said cap.

3. In a sewing machine, the combination with a tubular work-supporting arm, of a longitudinally movable slide mounted thereon, an end-cap fitted to the outer extremity of the arm and affording a housing for a loop-taker mounted in said arm, a pivotal connection between said cap and the slide, and a stop for preventing the turning 20 of said cap upon its supporting slide while in position to embrace the loop-taker.

4. In a sewing machine, the combination with a tubular work-supporting arm provided with a lateral slideway and an adjacent stop-shoulder, a slide-bar fitted to said 25 slideway and provided with a transverse

stop-pin adapted to engage said stop-shoulder to limit the motion of said slide-bar toward the end of the arm, an end-cap fitted to the outer extremity of the arm and affording a housing for a loop-taker mounted upon said arm and a pivotal connection between said cap and the slide-bar.

5. In a sewing machine, the combination with a tubular work-supporting arm, of a throat-plate secured upon said arm and overhanging its forward extremity, a stop-pin upon and adjacent one edge of the throat-plate, a cylindrical end-cap fitted to the extremity of said arm and having a longitudinal shoulder adapted to engage said stop-pin, a longitudinally movable slide mounted upon said arm, and a pivotal connection between the end-cap and said slide.

In testimony whereof, I have signed my name to this specification, in the presence of two subscribing witnesses.

GEORGE E. MOLYNEUX.
